UNITED STATES PATENT OFFICE.

CONSTANT T. CUNDALL, OF STONINGTON, CONNECTICUT, ASSIGNEE TO C. B. COFFRELL & SONS COMPANY, OF NEW YORK, N. Y., A CORPORATION OF NEW JERSEY.

PLATE-REGISTERING DEVICE FOR PLATE-CYLINDERS OF PRINTING-PRESSES.

1,070,669.

Specification of Letters Patent. Patented Aug. 19, 1913.

Application filed December 2, 1911. Serial No. 663,530.

To all whom it may concern:

Be it known that I, CONSTANT T. CUNDALL, a citizen of the United States, and resident of Stonington, in the county of 5 New London and State of Connecticut, have invented a new and useful Improvement in Plate-Registering Devices for Plate-Cylinders of Printing-Presses, of which the following is a specification.

10 The object of this invention is to provide a device which can be readily attached to and detached from the plate cylinder and in which the registering pointer or pointers may be readily brought to the desired registry position and secured in such position.

15 A practical embodiment of my invention is represented in the accompanying drawings, in which—

Figure 1 represents the device temporarily mounted upon a plate cylinder, intermediate portions of the cylinder and cross bar being broken away so that both ends of the cylinder and device may be illustrated on a proper scale, Fig. 2 is a detail section taken 20 in the plane of the line A—A of Fig. 1, Fig. 3 is a detail section taken in the plane of the line B—B of Fig. 1, Fig. 4 is a detail section taken in the plane of the line C—C of Fig. 2, Fig. 5 is an enlarged detail view in 25 side elevation of a portion of the cross bar showing one pair of coacting trammels, and Fig. 6 is a cross section taken in the plane of the line D—D of Fig. 5, the pointer being shown in its depressed position in dotted lines.

The plate cylinder is denoted by 1, the bearers at its ends by 2, and the plate cylinder gears by 3. The plates on the cylinder are denoted by 4. The plate registering device comprises a cross bar 5 having its cylindrical ends 6 mounted in lugs 7, uprising from the outer members 8 of the end supports, the inner members of said supports being denoted by 9. These outer and 40 inner members 8 and 9 are curved to conform to the periphery of the cylinder and the inner members are interlocked with the cylinder for temporarily holding the cross bar in a fixed position with respect to the cylinder, in the present instance by providing the inner members 9 with a series of teeth 10 which interlock with the teeth of

the plate cylinder gears 3. These inner members 9 may further be provided with flanges 11 along their inner sides overlapping the inner sides of the bearers 2 for holding the device against lateral movement with respect to the plate cylinder when mounted thereon.

Adjusting screws 12 carried by the outer members 8 of the end supports for the cross bar 5 engage lugs 13 projecting from the inner members 9 through circumferentially elongated slots 14 in the outer members 8 for adjusting the outer members 8 along the inner members 9 to shift the cross bar 5 circumferentially along the plate cylinder 1. Clamp screws 15 carried by the lugs 7 of the outer members 8 serve to clamp the cross bar 5 to the said outer members of the end supports.

One or more registering pointers 16, in the present instance three are shown, may be provided for properly registering the position of the plate or plates 4, which pointers are adjusted circumferentially along the cylinder by the adjustment of the outer members 8 of the end supports. These pointers may be also adjusted in a right line along the cross bar 5. They may also be adjusted in circular paths about their longitudinal axes.

The means which I have shown for securing the adjustment of each pointer along the cross bar and in a circular path about its longitudinal axis, are constructed, arranged and operated as follows:—A pair of trammels 17, 18, are movable along the cross bar 5. To lock the trammel 17 to the cross bar at different predetermined points along the same, the cross bar is provided with a series of notches 19 and the trammel is provided with a set screw 20 having a pointed end 21 arranged to enter one of the notches 19. This will prevent any danger of the trammel 17 slipping out of its adjusted position on the bar. This trammel 17 carries an adjusting screw 22, the screw threaded portion 23 of which engages the trammel 18 and serves to adjust the trammel 18 toward and away from the trammel 17, the length of the screw being preferably such that the trammel 18 may be adjusted along the bar more than the distance between two suc-

cessive notches 19. After the trammel 18 has been adjusted to the proper position, it 5 may be clamped in such position by the set screw 24. A vertically arranged bushing 25 is rotatably mounted in the trammel 18, said bushing being provided with a head 26 for facilitating the rotative adjustment of said bushing.

The pointer 16 extends eccentrically 10 through the bushing 25 and the said bushing is provided with an eccentric recess 27 in which is located a spring 28 interposed between the bottom of the recess and a collar 29 on the pointer 16 for normally holding 15 the pointer raised away from the plate 4 on the cylinder 1. This pointer may be provided with a collar 30 forming a stop to limit the upward movement of the pointer. This pointer may also be provided at its 20 upper end with a handle 31 for ready use by the operator when desired to depress the pointer into engagement with the plate for registering purposes.

A clamp screw 32 extends through split 25 portions 33, 34, of the trammel 18 for securing the bushing in its different rotative adjustments.

From the above description it will be seen that the pointer 16 may be adjusted 30 circumferentially along the cylinder by the adjustment of the outer members 8 of the end supports for the cross bar 5. It will also be seen that the pointer may also be rapidly brought into an approximate position 35 by the movement of the trammels along the cross bar 5 and then adjusted to the utmost nicety along the said bar after one trammel has been locked to the bar. After this longitudinal adjustment has been completed, 40 the trammel which carries the pointer may then be clamped to the bar. The pointer may also be readily adjusted in a circular path about its longitudinal axis by turning the bushing 25 and a ready means is provided for constantly testing the 45 position of the pointer by depressing the same without releasing any of the parts. After the pointer has been brought to the proper position, the bushing 25 may then be secured in such position.

It is evident that slight changes might be resorted to in the form, construction and arrangement of the several parts without departing from the spirit and scope of my 55 invention; hence I do not wish to limit myself strictly to the structure herein set forth, but

What I claim is:—

1. In a device of the character described, 60 a cross bar, means for temporarily mounting it in a fixed position on the plate cylinder, a pointer and means for adjusting the pointer along the bar.

2. In a device of the character described, 65 a cross bar, means for temporarily mount-

ing it in a fixed position on the plate cylinder, a depressible pointer, means for automatically returning the pointer to its raised position, and means for adjusting the pointer along the bar.

3. In a device of the character described, 70 a cross bar, means for temporarily mounting it in a fixed position on the plate cylinder, a pointer, means for adjusting the pointer along the bar and means for securing the pointer in its adjusted position.

4. In a device of the character described, 75 a cross bar, means for temporarily mounting it in a fixed position on the plate cylinder, a depressible pointer, means for automatically returning the pointer to its raised position, means for adjusting the pointer along the bar and means for securing the pointer in its adjusted position.

5. In a device of the character described, 80 a cross bar, means for temporarily mounting it in a fixed position on the plate cylinder, a pointer and means for adjusting the pointer to different positions in a circular path about its longitudinal axis.

6. In a device of the character described, 85 a cross bar, means for temporarily mounting it in a fixed position on the plate cylinder, a depressible pointer, means for automatically returning the pointer to its raised 90 position and means for adjusting the pointer to different positions in a circular path about its longitudinal axis.

7. In a device of the character described, 95 a cross bar, means for temporarily mounting it in a fixed position on the plate cylinder, a pointer, means for adjusting the pointer to different positions in a circular path about its longitudinal axis and means for securing the pointer in its adjusted position.

8. In a device of the character described, 100 a cross bar, means for temporarily mounting it in a fixed position on the plate cylinder, a depressible pointer, means for automatically returning the pointer to its raised 105 position, means for adjusting the pointer to different positions in a circular path about its longitudinal axis and means for securing the pointer in its adjusted position.

9. In a device of the character described, 110 a cross bar, means for temporarily mounting it in a fixed position on the plate cylinder, a pointer, means for adjusting the pointer along the bar and means for adjusting the pointer to different positions in a 115 circular path about its longitudinal axis.

10. In a device of the character described, 120 a cross bar, means for temporarily mounting it in a fixed position on the plate cylinder, a depressible pointer, means for automatically returning the pointer to its raised 125 position, means for adjusting a pointer along the bar and means for adjusting the pointer to different positions in a circular path about its longitudinal axis.

11. In a device of the character described, a cross bar, means for temporarily mounting it in a fixed position on the plate cylinder, a pointer, means for adjusting the pointer along the bar, means for adjusting the pointer to different positions in a circular path about its longitudinal axis and means for securing the pointer in its adjusted position.
12. In a device of the character described, a cross bar, means for temporarily mounting it in a fixed position on the plate cylinder, a depressible pointer, means for automatically returning the pointer to its raised position, means for adjusting the pointer along the bar, means for adjusting the pointer to different positions in a circular path about its longitudinal axis, and means for securing the pointer in its adjusted position.
13. In a device of the character described, a pointer carrying cross bar arranged to be temporarily mounted on the cylinder and means for adjusting the cross bar circumferentially along the cylinder.
14. In a device of the character described, a pointer carrying cross bar arranged to be temporarily mounted on the cylinder and means for adjusting the cross bar circumferentially along the cylinder comprising end supports having inner members arranged to be interlocked with the cylinder and outer bar carrying members movable along the inner members.
15. In a device of the character described, a pointer carrying bar arranged to be temporarily mounted on the plate cylinder and means for adjusting the bar circumferentially along the cylinder comprising end supports having inner members provided with teeth arranged to be interlocked with the plate cylinder gears and outer bar carrying members movable along the inner members.
16. In a device of the character described, a pointer carrying cross bar arranged to be temporarily mounted on the cylinder and means for adjusting the cross bar circumferentially along the cylinder comprising end supports having inner members arranged to be interlocked with the cylinder, outer bar carrying members and adjusting screws engaging the two members.
17. In a device of the character described, a pointer carrying cross bar arranged to be temporarily mounted on the plate cylinder and means for adjusting the cross bar circumferentially along the cylinder comprising end supports having inner members provided with teeth arranged to interlock with the plate cylinder gears, outer bar carrying members and adjusting screws engaging the two members.
18. In a device of the character described, ing it in a fixed position on the plate cylinder, a pair of trammels movable along the cross bar, means for clamping one trammel to the cross bar, an adjusting screw carried by one trammel engaging the other trammel for adjusting it along the cross bar, a pointer carried by the last-named trammel and means for adjusting the pointer to different positions in a circular path.
19. In a device of the character described, a cross bar, means for temporarily mounting it in a fixed position on the plate cylinder, a pair of trammels movable along the cross bar, means for clamping one trammel to the cross bar, an adjusting screw carried by one trammel engaging the other trammel for adjusting it along the cross bar, a pointer carried by the last-named trammel, means for adjusting the pointer to different positions in a circular path, and means for clamping the pointer in its adjusted position.
20. In a device of the character described, a cross bar, means for temporarily mounting it in a fixed position on the plate cylinder, a trammel movable along the bar, a depressible pointer carried thereby and means for automatically returning the pointer to its raised position.
21. In a device of the character described, a cross bar, means for temporarily mounting it in a fixed position on the plate cylinder, a trammel movable along the cross bar, means for clamping it to the cross bar, a depressible pointer carried by the trammel and means for automatically returning the pointer to its raised position.
22. In a machine of the character described, a cross bar, means for temporarily mounting it in a fixed position on the plate cylinder, a trammel movable along the cross bar, a rotary adjustable bushing mounted in the trammel, and a pointer mounted eccentrically in the bushing.
23. In a machine of the character described, a cross bar, means for temporarily mounting it in a fixed position on the plate cylinder, a trammel movable along the cross bar, a rotary adjustable bushing mounted in the trammel, and a normally raised depressible pointer mounted eccentrically in the bushing.
24. In a machine of the character described, a cross bar, means for temporarily mounting it in a fixed position on the plate cylinder, a trammel movable along the cross bar, a rotary adjustable bushing mounted in the trammel, a pointer mounted eccentrically in the bushing and means for clamping the bushing in its different rotative positions.
25. In a machine of the character described, a cross bar, means for temporarily mounting it in a fixed position on the plate

bar, a rotary adjustable bushing mounted in the trammel, a normally raised depressible pointer mounted eccentrically in the bushing, and means for clamping the bushing in its different rotative positions.

In testimony, that I claim the foregoing as my invention, I have signed my name in

presence of two witnesses, this twenty-ninth day of November A. D. 1911.

CONSTANT T. CUNDALL.
